UNITED STATES PATENT OFFICE.

THOMAS W. S. PHILLIPS, OF NEW YORK, N. Y.

TOILET-POWDER BOX.

1,264,555.

Specification of Letters Patent. Patented Apr. 30, 1918.

Application filed January 25, 1917. Serial No. 144,384.

To all whom it may concern:

Be it known that I, THOMAS W. S. PHILLIPS, a citizen of the United States, and a resident of the city, county, and State of 5 New York, have invented a certain new and useful Improvement in Toilet-Powder Boxes, of which the following is a specification.

This invention relates to boxes for holding 10 toilet powders and specifically to that character of powder box disclosed in the U. S. patent to E. M. Lichtenstein, No. 697,729 dated April 15, 1902.

This invention resides in the novel construction and combination of parts herein-after described and finally pointed out in the appended claim.

Reference is to be had to the accompanying drawings, forming part hereof, in 20 which—

Figure 1 is a side elevation of my improved powder box,

Fig. 2 is a vertical sectional elevation of the same,

Fig. 3 is a plan view of the tray, and, 25 Fig. 4 is a sectional elevation of a portion of the bottom of the tray.

Throughout the various views of the drawings, similar reference characters designate similar parts.

As heretofore stated, this invention relates to an improvement on a powder box of the type disclosed in the Lichtenstein patent, above referred to. In the construction therein disclosed, the powder is too 35 extravagantly used and when, at times, dampness causes the powder to cake in the box it is very difficult to remove. My improved box readily overcomes these difficulties.

In the preferred form of my invention, as 40 illustrated in the accompanying drawing 1 indicates the portion of the box utilized for containing the powder, the powder contained therein being indicated at 6. This containing portion 1 is provided with an inner circumferential wall 10, over which the cover 2 snugly fits and is frictionally held thereon.

50 A tray 3 loosely fits the interior of the

portion 1 and is utilized to support chamois, powder puff or the like for the application of the powder to the person. This tray 3 consists of a circumferential wall 4 and bottom 5 and is supported by resting on 55 top of the powder 6 in the box.

A plurality of perforations 7 are formed in the bottom 5 of the tray, these perforations being grouped together in one portion of the bottom 5, the major portion 60 of the bottom being preferably imperforate so that powder can only pass through a portion of the bottom 5, that is, through said openings 7, the imperforate portion of the bottom being utilized for the even spreading 65 of the powder so that the same is received in even quantities upon the puff or chamois.

At times the powder in the box becomes 70 slightly caked and is difficult to remove. In order that the same may be loosened to readily pass through the openings 7 protuberances 8 are formed by forcing the material of the bottom of the tray in the perforations, downward, as shown in Fig. 75 4. By rotating the tray in the box these protuberances 8 serve to loosen the caked powder so that the same readily passes through the openings 7 and rides up on the imperforate portion of the bottom where it 80 is evenly spread. In order that the tray 3 may be removed from the box when desired the wall 4 is provided with tabs 9 so that the tray can be readily grasped 85 thereby and lifted out.

From the foregoing it is obvious that my invention is not to be restricted to the embodiment herein shown but is broad enough to cover all structures coming within the scope of the annexed claim.

90 What I claim is:

In an article of the class described, the combination of a box having a loosely fitting tray contained within the same, said tray having a flat bottom and an annular 95 circumferential wall extending about the edge of said bottom, the bottom of said tray having a plurality of perforations grouped together and extending from the side wall of the tray toward its center, with the major 100

portion of the bottom of the tray imperforate to form a powder spreading surface, so that rotation of the tray causes powder to pass through the perforations onto the 5 imperforate surface, and a plurality of powder loosening protuberances on the bot-

tom of the tray formed by forcing the material of the bottom downwardly and out of the perforations formed therein.

Signed at the city, county and State of 10
New York this 24th day of January 1917.
T. W. S. PHILLIPS.
